(57) **CLAIM**

We claim a novel design for a boot tray, as shown and described.

DESCRIPTION

FIG. 1 is a top perspective view of the tray;

FIG. 2 is a plan view of the tray;

FIG. 3 is a front view of the tray;

FIG. 4 is a back view of the tray;

FIG. 5 is a left side view of the tray;

FIG. 6 is a right side view of the tray; and,

FIG. 7 is a magnified sectional view taken substantially along Line 7-7 of FIG. 2.

The bottom surface of the tray is unadorned and forms no portion of the design.
